UNITED STATES PATENT OFFICE.

THÉOPHILE SAVARY, OF PARIS, FRANCE.

RADIATOR.

Application filed January 26, 1923. Serial No. 615,180.

To all whom it may concern:

Be it known that I, THÉOPHILE SAVARY, a citizen of the Republic of France, residing at 110 Boulevard de Clichy, Paris, France, have invented certain new and useful Improvements in Radiators, of which the following is a specification.

This invention relates to radiators; and it proposes, briefly, an improved article of 10 the character indicated which may be used either by itself or combined with other apparatus of the same type, for the heating, with hot water or steam at low pressure, of rooms, houses, hot houses and the like, 15 but which may also be used for cooling purposes either by employing a freezing mixture or chemicals, or by utilizing the expansion of compressed gas to produce a considerable temperature lowering.

20 Two embodiments of my invention are illustrated in the accompanying drawings, wherein:

Figure 1 is a part-sectional front elevation of one form;

25 Fig. 2 is a part-sectional side elevation thereof;

Fig. 3 is a part-sectional front elevation of the second or preferred form;

29 Fig. 4 is a part-sectional side elevation of Fig. 3;

Fig. 5 is a diagrammatic horizontal section on line 5—5, Fig. 3;

Fig. 6 is a plan view of Fig. 3.

Referring more particularly to the drawings, my invention comprises, in both forms, two lower metal tanks I and K soldered at their rims to a plate *a*; an upper metal tank *c* soldered to a plate *b* and containing a vertical partition wall *d*; and 40 a system of connecting pipes.

The pipe system, as shown, comprises two horizontal pipes L and M (represented in dotted lines in Fig. 5) which connect the tanks I and K and, hence, are disposed beneath plate *a* and are provided with valves L' and M'; and two other horizontal pipes N and O which are disposed above said plate and are provided with valves N' and O', and which connect, respectively, two pairs of vertical pipes R and S and P and Q, hereinafter termed the main vertical pipes. These four pipes P, Q, R and S are indicated in section in Fig. 5 and in dotted lines in Fig. 6; in Figs. 1 and 3, the pipes P and Q are concealed behind pipes S and R, and

in Figs. 2 and 4 pipes P and S are concealed behind pipes Q and R. Two sets of secondary vertical pipes I' and K' are also comprised in the system and are furnished 60 with tinned metal fins or ribs; the pipes I' connecting the lower tank I to the upper tank *c*, and the pipes K' connecting tank *c* and the other lower tank K.

The tank I may be used as a boiler and 65 may, therefore, be heated in any suitable way—for instance, by means of a gas burner H' which is arranged in an open-bottomed chamber (Figs. 1-4) formed by a depending wall H² provided at the bottom 70 of said tank. The burner may, of course, be supplied with gas in any desired manner and it may, if preferred, be replaced by some other type of heater.

When it is desired to use the structure 75 above described for hot-water heating, the cap *t* of the upper tank *c* is removed and water is fed into tank I by means of a funnel, the stem of which projects into the upper end of pipe R, the latter terminating 80 flush with plate *b*. The water in tank I flows into tank K through the pipes L and M, filling both pipes and driving out the air; it then rises in all the vertical pipes until it reaches and flows over the upper 85 ends thereof, the pipe R being filled first. The air driven out by the rising water is discharged through a small vent tube *u* (Figs. 1, 3 and 6) and through the opening 90 for the cap *t*.

The apparatus is thus completely filled and no more air left therein, which is an important feature of the invention because in the absence of air the boiling point of the water is lowered. Tank I is then heated; the valves L', M', N', O' of the four pipes L, M, N, O being closed at first for some minutes and, in consequence, cutting out communication between tanks I and K and between pipes P and Q and pipes S and R, so that the water heated in tank I cannot pass into tank K nor into the pipes P and S connected thereto. The water in tank I becomes lighter when heated and rises in the pipes I', Q and R connected to this tank and flows out into the upper tank *c*. The four valves L', M', N', O' are then opened, and warm water from tank *c* forces out the cooler water in the pipes K', P and S and the tank K, thus producing a discharge 100 into the tank I, through the pipes L, M, N, O, of the water contained in the 105 tank K. The water in tank I is then heated and rises in the pipes I', Q and R connected to this tank and flows out into the upper tank *c*. The four valves L', M', N', O' are then opened, and warm water from tank *c* forces out the cooler water in the pipes K', P and S and the tank K, thus producing a discharge 110 into the tank I, through the pipes L, M, N, O, of the water contained in the tank K.

pipes and the tank K, due to the varied densities of the water in the pipes and in both tanks.

The water in tank I becomes hotter and hotter, and flows into the tank c, driving out and taking the place of the cooler water contained therein, which is heavier and flows down to tank K through the pipes K', P and S, and through the four connecting pipes L, M, N, O to tank I to be heated. The water thus circulates in a closed path, giving up its heat to the air of the rooms by means of the great heating surface of the numerous ribs or fins.

When the above apparatus is to be used for heating with steam at low pressure, the lower tanks I and K are three-quarters filled with water, the tank K being here used as an auxiliary tank. The tank I is then heated underneath; and the steam generated by the heat, being lighter than the air contained in the system, rises through the several pipes I', Q, R to the upper tank c which it fills and where it gradually becomes cool. The cooled steam becomes heavier and is driven out of tank c by in-flowing hotter steam, and flows down through the pipes K', P, S to tank K. The opening of the pipes N, O produces an exhaustion of air and steam from tank K, through said pipes into tank I, where the mixture is heated and, when lighter, rises through pipes I', Q, R to tank c and follows the same circuit.

As previously stated, the apparatus may also be used as a cooling device for food preservation, as a refrigerating device for drinks and as a device for maintaining a fresh temperature during hot summer days. For this purpose, a hermetic closure V with which the top of the upper tank c is provided, is removed; and through the aperture thus exposed, the said tank is filled with the usual freezing mixture of salt and crushed ice, or with any other liquid, solid or gaseous chemicals for producing a low temperature, either directly in the case of solid products, or by expansion in the case of liquid and gaseous substances, the air in the room thus being cooled by contact with the tanks, the piping and the fins. Removable caps W, X, Y and Z (Figs. 1 and 3) may be provided on the tanks to discharge the sediment and for cleaning purposes.

Figs. 3 to 6 show a preferred form of the invention which, as will be understood from a comparison thereof with Figs. 1 and 2, merely involves the addition of certain parts or features to the structure illustrated in the latter figures, the two constructions being otherwise identical. These added parts comprise a suitable number of auxiliary vertical pipes H (four, six, eight or more) which connect the bottom of the

tank K to the tank c, an expansion chamber A, and an outlet pipe J for discharging the products of combustion from the burner H' or other heater chamber or casting H².

The pipes H, hereinafter termed "accelerators", are formed at their lower ends with horizontal parts H³ (Fig. 3) which extend partway across the bottom of the tank I and bridge the space between the latter and the tank K, and their upper ends are formed with horizontal parts H⁴ (Figs. 3 and 6) which extend at their free ends beneath the partition d. The expansion chamber A is mounted on top of the tank c, where it rests on a fixed insulating plate g (Fig. 3), and is connected at its bottom to the lower tank K by a vertical pipe B located externally of the previously-described piping. The outlet pipe J, as mentioned above, leads the burned gases and products of combustion from the burner chamber H², where it has a laterally-bent inlet end J' (Fig. 3) upwardly through the apparatus; its upper end being provided with an elbow J² (Fig. 4) which is located immediately under the upper plate b and which passes outwardly and then downwardly.

In operation, the tank I is heated from underneath, by means of the burner H' or other heating means employed, whereupon the water in said tank and in the accelerator pipes H is quickly brought to a boil. Hot water flows into tank c through pipes H, the outlet parts H⁴ of which are spread out or arranged fanwise (Fig. 6), and forcibly drives out the cold water in the pipes mounted on tank K. The quantity of hot water flowing up into the tank c is replaced by an equal quantity of cold water flowing from tank K; this cold water being heated by passing through the heating zone, and flowing up into tank c, and so on. Meanwhile, the water in tank I is heated, and begins its circulating movement as above explained.

The expansion chamber A, which is half-filled with water, serves as an auxiliary tank and thus insures the complete filling of the system with water. This chamber also acts as a regulator, and is used to balance the steam pressures produced in the apparatus. An abnormal pressure in the tank c will raise the water level in tank A by means of the pipe B, while the air enclosed in the upper portion of tank A will be compressed until balancing of the pressures in tanks A and C takes place. When the pressure ceases, the water in tank A returns to its normal level.

I claim:—

1. A radiator, comprising a pair of lower tanks, horizontal piping connecting the same for delivering fluid from one tank to

the other, a cover plate to which said tanks are secured, an upper plate, a tank mounted thereon, a set of main vertical pipes interposed between said plates and opening 5 through the same into the tanks, a set of secondary vertical pipes likewise interposed between said plates and opening through the same into said tanks, the secondary pipes being provided with fins, and horizontal 10 pipes connecting the opposite main pipes in pairs; substantially as described.

2. A radiator, comprising a pair of lower tanks, means for heating one of them, horizontal piping connecting said tanks for delivering fluid to the heated tank from the other, a cover plate to which said tanks are secured, an upper plate, a tank mounted thereon, a set of main vertical pipes interposed between said plates and opening 15 through the same into the tanks, a set of secondary vertical pipes likewise interposed between said plates and opening through the same into said tanks, the secondary pipes being provided with fins, horizontal pipes 20 connecting the opposite main pipes in pairs, an auxiliary tank for containing fluid mounted on the upper tank and providing an expansion chamber, and a vertical pipe 25 opening at opposite ends into the auxiliary tank and one of the lower tanks to enable the passage of fluid therethrough between said lower tank and said auxiliary tank; substantially as described.

3. A radiator, comprising upper and lower fluid-containing tanks, means for heating the lower tank, a system of vertical pipes interposed between the tanks and opening into them at opposite ends, an auxiliary fluid-containing tank located above the upper tank, and a pipe arranged externally of the vertical pipe system and opening at opposite ends into the auxiliary tank and the lower tank to enable the passage of fluid therethrough between said lower tank and said auxiliary tank; substantially as described.

4. A radiator, comprising upper and lower tanks, a system of vertical pipes interposed between the tanks and opening into them at opposite ends, a set of accelerator pipes opening at their upper ends into the upper tank and having horizontally-offset lower ends which open through the bottom of the lower tank, and means for heating 50 said lower tank and the offset ends of said accelerator pipes; substantially as described.

5. A radiator, comprising upper and lower fluid-containing tanks, a system of ver-

tical pipes interposed between the tanks and opening into them at opposite ends, a set of 60 accelerator pipes opening at their upper ends into the upper tank and having horizontally-offset lower portions which open through the bottom of the lower tank, means for heating said lower tank and the 65 offset ends of said accelerator pipes, an auxiliary fluid-containing tank mounted above the upper tank, and a pipe arranged externally of the apparatus and connected at opposite ends to the auxiliary and lower 70 tanks to enable the passage of fluid therethrough between said lower tank and said auxiliary tank; substantially as described.

6. A radiator, comprising an upper tank, a pair of spaced lower tanks, means for externally heating one of the lower tanks, horizontal piping connecting the two lower tanks, a system of vertical pipes interposed between the upper and lower tanks and opening into them at opposite ends, and a set of 80 accelerator pipes opening at their upper ends into the upper tank and having horizontally-offset lower portions which extend beneath the heated lower tank in proximity to said heating means so as to be heated thereby and which open at their free ends 85 through the bottom of the other lower tank; substantially as described.

7. A radiator, comprising an upper tank, a pair of lower tanks disposed in spaced, 90 parallel relation in a common horizontal plane, piping between the two lower tanks, and two sets of vertical pipes interposed between the upper and lower tanks, both sets opening at one end into the upper tank and 95 each set opening at the other end into one of the lower tanks; substantially as described.

8. A radiator, comprising an upper tank, a pair of lower tanks disposed in spaced, 100 parallel relation in a common horizontal plane, piping between the two lower tanks, two pairs of main vertical pipes and two sets of secondary vertical pipes connected at their upper ends to the upper tank, one 105 of said pairs of main pipes and one of said sets of secondary pipes having their lower ends connected to one of the lower tanks and the other pair of main pipes and other set of secondary pipes having their lower 110 ends connected to the other lower tank, and horizontal pipes connecting the opposite main pipes in pairs; substantially as described.

In testimony whereof I affix my signature.
THÉOPHILE SAVARY.
